UNITED STATES PATENT OFFICE.

GUSTAVE F. LINDQUIST, OF CHICAGO, ILLINOIS, ASSIGNOR TO UNION SPECIAL MACHINE COMPANY, OF CHICAGO, ILLINOIS, A CORPORATION OF ILLINOIS.

POWER-TRANSMITTING DEVICE.

1,276,379.

Specification of Letters Patent. Patented Aug. 20, 1918.

Application filed May 9, 1912. Serial No. 696,204.

To all whom it may concern:

Be it known that I, GUSTAVE F. LINDQUIST, a citizen of the United States, residing at Chicago, in the county of Cook, State 5 of Illinois, have invented certain new and useful Improvements in Power-Transmitting Devices, of which the following is a description, reference being had to the accompanying drawing, and to the figures of reference marked thereon.

The invention relates to new and useful improvements in power transmitting devices, and more especially to devices of this character which may be used in connection 15 with sewing machines where the power is transmitted from a power shaft through the transmitter to the stitching mechanism or other operating parts of a sewing machine.

An object of the invention is to provide 20 a transmitter wherein a dual drive may be derived from the transmitter.

A further object of the invention is to provide a transmitter of the above character with controlling devices whereby one of the 25 driven wheels may be controlled entirely independently of the other driven wheel.

These and other objects will in part be obvious and will in part be hereinafter more fully disclosed.

30 In the drawings which show by way of illustration one embodiment of the invention;

Figure 1 is a partial side elevation and a 35 partial sectional view showing a transmitter having my improvements applied thereto;

Fig. 2 is an end view of the same.

Prior to the present invention, it was common to provide a power transmitter which included a supporting frame 1, which 40 could be held by any convenient means such as screws or bolts to the under side of a bench or table. At the opposite ends of the frame are bearings 2 and 3, in which is mounted a rod 4. Secured to the rod 4 is a bracket arm 5 which is freely mounted on the rod so as to turn about the same. Said bracket 5 carries laterally projecting arms 6, 6, through which pass screws 7, 7. These screws are adapted to engage a supporting frame 1 and serve as a means for angularly adjusting the bracket about the pivotal rod 4 therefor. This bracket carries a sleeve 8 in which is secured a supporting shaft 9. These parts are all fully shown and described in the patent to Dudley S. Seymour,

No. 854,671, granted May 21st, 1907. In said patent is shown and described a driving member and a driven member, which members are adapted to be brought into engagement so that motion may be transmitted 60 from the driving member to the driven member. The present invention is an improvement on the transmitter shown and described in the above-mentioned patent, and consists broadly in providing two driven 65 members which may be brought into contact with a driving member, for the purpose of securing from the driving member a dual drive. The invention further contemplates the independent control of one of the driven 70 members whereby it may be caused to engage the driving member so that motion may be imparted thereto, while the other driven member is at rest.

Referring more in detail to the drawings, 75 the invention consists in providing the supporting shaft 9, with a driving wheel 10 which is free to turn on said supporting shaft, and which is also free to slide longitudinally thereon. Mounted on the shaft 9 80 is a driven wheel 11 which is located at one side of the driving wheel 10, and a driven wheel 12 which is located at the other side of the driving wheel 10. The driving wheel 10 as herein shown, is constructed so as to receive a flat belt. The side flanges 13 of the belt wheel are formed with brake surfaces 14 and 15. These brake surfaces are cone-shaped and are reversely located relative to each other. The driving wheel 11 is carried by 85 a sleeve 16 which is free to rotate on the shaft 9, and which may also be moved longitudinally thereof. Said sleeve 16 has an inwardly projecting reduced portion 17. A collar 18 rests against one side of the driving 90 wheel 10 and is also provided with a reduced portion similar to the reduced portion on the sleeve 16. A coiled spring 19 surrounds the reduced portions of the collar 18 and the sleeve 16. This spring normally 100 tends to separate the driving wheel 10 and the driven wheel 11. A second collar 20 is rigidly secured to the shaft 9 and limits the movement of the wheel 10 to the right, as viewed in Fig. 1. The driven wheel 11 is 105 formed with a V-shaped belt groove 21 adapted to receive a belt 22. Said driven wheel is also formed with an overhanging flange 23 carrying a leather friction pad 24. This overhanging flange 23 is so disposed 110

2

that its inner surface is substantially parallel with the conical surface 15 on the driving wheel 10 so that when the wheel 11 is moved relative to the wheel 10, said friction pad 24 may engage the conical surface 15 of the driving wheel, and the parts held so as to turn together. The driven wheel 11 is also formed with an annular brake flange 25 which is adapted to coöperate with the brake pad 26, carried by a bolt mounted in an arm 27 projecting from the bracket 5. This bolt 27 is adapted to be adjusted in the arm 27 and is held in adjusted position by a set nut 28. The driven wheel 12 is formed with a supporting sleeve 29 which is free to turn on the shaft 9, and abuts against a fixed collar 30 secured to the end of the shaft. Said sleeve 29 is formed with a reduced portion 31. On the opposite side of the driving wheel 10 is a second collar 32 having a reduced portion 33. A coiled spring 34 engages the reduced portions of the collar 32, and the sleeve 29 and said coiled spring normally tends to separate the driven member 12 and the driving member 10. Said driven member 12 is formed with an overhanging flange 35 which carries a friction pad 36 adapted to coöperate with the conical flange 14. Said driven wheel 12 is also provided with a V-shaped belt engaging surface 37 which is adapted to receive a cord belt 38. Said flange 35 is formed with a cylindrical brake surface 39 which is adapted to coöperate with a brake shoe 40.

35 A lever 41 is pivoted at 42 to the supporting bracket 5 and is provided with an eye 43 adapted to receive a rod whereby the lever may be shifted. Said lever carries a second arm 44, which is forked so as to extend to each side of the shaft 9, and bears against a collar 45 which is capable of sliding freely on the shaft 9. This collar 45 rests against the end of the sleeve 16. The lever 41 carries a third arm 46 which extends over the transmitter and carries a brake shoe 40. The brake shoe is adjustably secured to the free end of the arm 46, by a screw 47. The spring 34 between the driving member 10 and the driven member 12 is heavier than the spring 19 between the driving member 10 and the driven member 11, so that any pressure brought to bear against the driving and driven members will first collapse the spring 19 before collapsing the spring 34. The spring 34 as above noted, tends to separate the driving member 10, and the driven member 12, and will normally hold the driving member pressed against the collar 20 which is fixed to the shaft 9.

60 The spring 19 as above noted, tends to separate the driven member 11 and the driving member 10, and to hold the driven member 11 in contact with the brake shoe 26. A spring 48 is connected at one end to the

lever 41, and at its other end to the supporting frame for the transmitter. This spring normally tends to turn the lever 41 so as to hold the brake shoe 40 in engagement with the braking surface 39 on the driven member 12.

When the parts are in the position shown in Fig. 1, the driving and driven members are separated and the driven member 12 is held from turning by the brake shoe 40 through the action of the spring 48, while the driven member 11 is held from turning by the brake shoe 26 through the action of the spring 19. If the outer end 43 of the lever 41 is depressed, the spring 19 will be compressed and the driven member 11 moved from contact with the brake shoe 26, until the friction pad 24 engages the conical surface 15 of the driving member 10. This movement of the driven member 11, will cause said driven member to be engaged by and moved with the driving member 10. At this time the driven member 12 is stationary, and if desired, the releasing of the lever 43 will disconnect the driven member 11 from the driving member 10. It will therefore, be seen that the driving member 10 may be connected to the driven member 11 independently of any connection between the driving member 10 and the driven member 12. A further movement of the lever 41 will compress the spring 34 and move the driven member 11 and the driving member 10 bodily along the shaft 9 until the conical flange 14 of the driving member 10 engages the friction pad 36 carried by the flange 35 of the driven member 12. When these parts are brought into engagement, then both the driven member 11 and the driven member 12 will turn in unison with the driving member 10. The releasing of the lever 43 will first cause the driving member 10 to be separated from the driven member 12, owing to the fact that the spring 34 is of greater tension than the spring 19. This movement of the lever 43 will cause the brake pad to engage the driven member 12 and stop the same. A further releasing movement of the lever 41 allows the driven member 11 to be moved away from the driving member 10 as the lateral movement of the driving member 10 is limited by the collar 20 fixed to the shaft 9.

It will be obvious that from the above construction, I have provided a transmitter wherein two driven members may be successively connected with a driving member and a dual drive secured from a single driving member. This transmitter is especially useful in connection with a sewing machine for sewing heavy articles wherein the article to be sewed is conveyed by a traveling conveyer to the stitching mechanism. In such instance, the conveyer will be driven from the driven member 11, while the stitch-

ing mechanism will be driven from the driven member 12. By the proper manipulation of the transmitter, the conveyer can be actuated to bring the article to be stitched into the range of the stitching mechanism, after which a further movement of the transmitter will cause the stitching mechanism to operate to stitch the article as it is carried along past the stitching mechanism 5
 10 by the conveyer. This is only one instance of a practical use of the transmitter above described. It is obvious that the driven members may be used for driving two different mechanisms of any character, wherein it
 15 is desired to successively and independently control said mechanisms.

It is obvious that minor changes in the details of construction and arrangement of parts may be made, without departing from 20 the spirit of the invention as set forth in the appended claims. It is also obvious that instead of having the driving member in the center, and the driven members on each side thereof, that these members may be arranged 25 in other relations to each other, the essential feature being that the driving member contacts first with one driven member and then the other, so as to secure the successive drives.

30 Having thus particularly described my invention, what I claim as new and desire to secure by Letters Patent, is:—

1. A power transmitter including in combination a driving wheel, two driven wheels 35 normally disconnected from the driving wheel, and means for connecting first one driven wheel to the driving wheel and for subsequently connecting the other driven wheel to the driving wheel while the first mentioned driven wheel is connected to the driving wheel.

2. A power transmitter including in combination a driving wheel, two driven wheels normally disconnected from the driving 45 wheel, yielding means for normally holding the driven wheels out of contact with the driving wheel and means for connecting first one driven wheel to the driving wheel and for subsequently connecting the other driven 50 wheel to the driving wheel while the first mentioned driven wheel is connected to said driving wheel.

3. A power transmitter including in combination, a driving member, a driven member on each side of the driving member, said driving and driven members having coöperating friction surfaces, springs for normally separating the driven members from the driving member and a single lever for 60 causing first one driven member and then the other to engage said driving member.

4. A power transmitter including in combination a supporting shaft, a driven mem-

ber free to turn on said shaft and held from lateral movement thereon, a driving member free to turn on said shaft and laterally movable thereon, a second driven member free to turn on said shaft and capable of moving laterally thereon, springs for normally separating the driven members from the driving member, and means for moving the last named driven member laterally into engagement with the driving member, and the driving member laterally into engagement with the first-named driven member. 65
 70
 75

5. A power transmitter including in combination a supporting shaft, a driven member free to turn on said shaft and held from lateral movement thereon, a driving member free to turn on said shaft and laterally 80 movable thereon, a second driven member free to turn on said shaft and capable of moving laterally thereon, a spring between the first driven member and the driving member, a spring between the second driven and the driving member, said last-named spring being of less tension than the first-named spring, and means whereby the last-named driven member may be moved into 85 engagement with the driving member and 90 the driving member moved into engagement with the first-named driven member.

6. A power transmitter including in combination a supporting bracket, a shaft carried thereby, a driven member mounted on said shaft and held from lateral movement thereon, a driving member mounted on said shaft and free to slide laterally thereon, a spring intermediate the driven member and the driving member, a collar secured to the 95 shaft and limiting the movement of the driving member through the action of said spring, a second-named driven member freely mounted on said shaft and capable of moving laterally thereon, a spring interposed between the driving member and the second-named driven member, said driven member having conical friction surfaces formed thereon, said driven members having overhanging flanges adapted to coöperate 100 respectively with the conical friction surfaces of the driving member, the spring between the first driven member and the driving member being of greater tension than the spring between the second driven member and the driving member, and means for 105 moving the second driven member into contact with the driving member, and the driving member into contact with the first-named driven member. 110
 115

In testimony whereof, I affix my signature in the presence of two witnesses.
